UNITED STATES PATENT OFFICE.

ALBERT BROADMEYER, OF HARRISBURG, PENNSYLVANIA, ASSIGNOR TO W. O. HICKOK MANUFACTURING COMPANY, OF HARRISBURG, PENNSYLVANIA, A CORPORATION OF PENNSYLVANIA.

GAGE OR GATE MECHANISM.

1,344,167.

Specification of Letters Patent. Patented June 22, 1920.

Application filed September 22, 1919. Serial No. 325,371.

To all whom it may concern:

Be it known that I, ALBERT BROADMEYER, a citizen of the United States, residing at Harrisburg, in the county of Dauphin and State of Pennsylvania, have invented certain new and useful Improvements in Gage or Gate Mechanisms, of which the following is a specification.

The present invention relates to means for determining the passage of paper or other work into ruling machines and the like.

The object is to provide a relatively simple structure, which can be adjusted so as to insure its proper operation and synchronism with the other mechanisms of the machine.

An embodiment of the invention which is at present considered the preferable one, is illustrated in the accompanying drawings, wherein:—

Figure 1 is a plan view of the gage with portions shown in section.

Fig. 2 is a cross sectional view,

Fig. 3 is a sectional view at right angles to Figs. 1 and 2 and substantially on the line 3—3 of Fig. 1,

Fig. 4 is a side elevation with portions broken away,

Fig. 5 is a cross sectional view through the rock shaft and one of the stop finger supports,

Fig. 6 is a detail longitudinal sectional view through one end of the rock shaft and its mounting.

Similar reference numerals designate corresponding parts in all the figures of the drawings.

In the embodiment illustrated, a suitable supporting frame is employed, portions of the longitudinal frame bars being illustrated at 7. Between these frame bars operates a work-conveying belt, a portion of which is illustrated at 8. Upon this belt are a plurality of longitudinally disposed cords 9 that serve to hold the work in the form of paper sheets or the like against slipping during the passage of such sheets through the machine. A plurality of rollers 10, 11 and 12 support the belt 8 in the frame, the rollers being journaled in boxes 13 slidably in guideways 14 formed in brackets 15 that are secured to the inner sides of the frame bars 7. The boxes are vertically adjusted by means of screws 16 journaled in the brackets

and having threaded engagement with said boxes.

Mounted longitudinally upon the frame bars 7 are base plates 17 having longitudinal guideways 18 in which are mounted slides 19 and 20. The rear slide is normally fixed against movement by a set screw 21, and the front slide is adjusted by a horizontal screw 22 threaded thereinto and having a bearing 23 on one end of the base plate. This screw is held against accidental rotation by a set screw 24 engaging thereon. Carried by the slides 19 and 20 are standards 25 provided at their upper ends with heads 26 having inwardly opening sockets 27.

A rock shaft 28 extends across the conveyer belt 8 and is provided with terminal sockets in which are slidably located supporting stems 30 that project from the ends of the shaft and have terminal balls 31 located in the sockets 27, and retained therein by plugs 32. The rock shaft is thus mounted to turn and can be shifted at either or both ends by adjusting the slides 19 and 20. Slidably mounted on the rock shaft 28 are collars 33 normally held against sliding movement and against rotation on the rock shaft by set screws 34 passing therethrough and engaging in a groove or keyway 35 formed longitudinally in the shaft. The collars 33 have outstanding ears 36 provided with bores 37 in which are adjustably mounted stop fingers 38 that are held in place by set screws 39. The lower ends of these fingers are preferably tapered, as illustrated in Fig. 3, and are adapted to move into and out of engagement with the belt 8 between the cords 9, accordingly as the rock shaft is actuated.

Extending longitudinally of one of the frame bars 7, and consequently transversely of the rock shaft 28 is a main driving shaft 40 on which is mounted a face cam 41, and co-operating with this face cam, is a depending arm 42 of a bell crank 43, the said arm having journaled on its free terminal a roller 44 that operates against the face of the cam 41. The other arm 45 of the bell crank extends in a generally horizontal direction beneath the shaft 28 and terminates in a bearing plate 46. Secured to the rock shaft 28 by a set screw 47 is a collar 48 having a crank arm 49 through which is adjustably threaded a bearing screw 50

that rests upon the plate 46 and is held against accidental displacement by a lock nut 51. The rock shaft 28 has affixed thereto another crank arm 52, to the free end of which is connected a spring 53 that is also connected to an adjusting screw 54 threaded into a bracket 55 on the adjacent frame bar 7. The action of this spring is to turn the rock shaft in a direction to raise the stop pins 38 from the belt 8, while the cam when rotated will, through the bell crank 43, serve to move the rock shaft in a direction to depress the stop fingers to the belt against the action of the spring. The bell crank 43 is journaled on a pivot stem 56 slidably mounted in a bearing piece 57 that is secured transversely to the upper side of the front frame bar 7. It is normally held against longitudinal adjustment by a set screw 58, but when said set screw is loosened, the pivot stem 56 can be moved through the medium of an adjusting screw 59 journaled as shown at 60 in the bearing piece 57 and having a threaded engagement in the inner end of said pivot stem.

In operation the cam 41, being rotated, will cause the bell crank to be periodically rocked, and this bell crank constituting an actuating member, will transmit motion periodically to the bell crank 49, constituting an actuated member. The stop fingers will thus be held for a predetermined period upon the belt, and a sheet of paper introduced between the cords 9 and the belt 8 will be moved to a position against said stop fingers. As the cam continues to rotate, the bell crank will be released, permitting the spring 53 to act and raise the fingers 38, whereupon the paper will pass on to the other instrumentalities, as for example, ruling mechanism. It will be noted that with this structure the fingers can be individually adjusted toward and from each other, so that they can be properly positioned with respect to the cords 9, and can thus be always placed in non-interfering relation to the cords. This is particularly useful in ruling mechanism, wherein the cords must in turn be so positioned that they will not interfere with the ruling pens. Either end of the rock shaft can be adjusted longitudinally along the conveyer belt, so as to insure that the fingers will all register and be abutted against the advance edge of the paper. Any defect or discrepancy therefore due to the cutting or shape of the paper can be accommodated. Furthermore the rock shaft can be adjusted bodily by correspondingly moving both slides 19 and 20 in order to insure the proper synchronization of the gage or stop mechanism with the other means that operates on the paper. Furthermore by adjusting the pivot stem through the medium of the screw 59, the position of the roller 44 and bell crank 43

can be varied with respect to the driving cam 41, and in this way the time of action of the gage or gate can be varied.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. In gage mechanism of the character set forth, the combination with a movable stop, of means for moving the same, including an actuated element having a path of movement in one plane, an actuating element for periodically moving the actuated element and having a path of movement in a plane transverse to the first plane, and means for varying the relative positions of the elements to change the time of operation of the actuated element by the actuating element.

2. In gage mechanism of the character set forth, the combination with a movable stop, of means for moving the same, including an actuated element that transmits movement to the stop, an actuating element for periodically moving the actuated element, and means for changing the position of the actuated element with respect to the actuating element and the stop while maintaining its operative relation to the latter to alter the time of operation of the actuated element by the actuating element.

3. In a gage mechanism of the character set forth, the combination with a movable stop, of means for moving the same, including a rocker arm, a cam for moving the arm having an axis of movement transverse to the axis of movement of the rocker arm, and means for relatively shifting the cam and arm to vary the time of operation of the arm by the cam.

4. In gage mechanism of the character set forth, the combination with a movable stop, of means for moving the same, including a rocker arm that transmits motion to the stop, a cam for moving the arm, and means for shifting the arm with respect to the cam and stop while maintaining its co-operative relation to the latter, to vary the time of operation of the arm by the cam.

5. In gage mechanism of the character set forth, the combination with a movable stop, of means for moving the same, including a rocker arm, a cam for moving the arm, a sliding support on which the rocker arm is pivoted, and means for holding the support in different positions to maintain the arm

in different relations with respect to the cam.

6. In gage mechanism of the character set forth, the combination with a movable stop 5 including a rock shaft having a crank arm, a rocker arm operating the crank arm, and a cam that operates the rocker arm and having an axis of movement transverse to that of the rock shaft.
- 10 7. In gage mechanism of the character set forth, the combination with a movable stop, including a rock shaft having a crank arm, a driving shaft located transversely of the rock shaft, a cam on the driving shaft, and 15 a rocker arm transmitting motion from the cam to the crank arm.

8. In gage mechanism of the character set forth, the combination with a movable stop, including a rock shaft having a crank arm, 20 a driving shaft disposed transversely to the rock shaft, a face cam on the driving shaft, and a pivoted bell crank rocker member having one arm engaged by the cam and having another arm operating on the crank 25 arm.

25 9. In gage mechanism of the character set forth, the combination with a movable stop, including a rock shaft having a crank arm, a rocker arm operating the crank arm, a cam that operates the rocker arm, and a 30 shiftable mounting for the rocker arm that permits its adjustment with respect to the cam, said rocker arm and crank arm having portions that remain in coaction when the 35 rocker arm is adjusted to different positions with respect to the cam.

10. In gage mechanism of the character set forth, the combination with a movable stop, including a rock shaft having a crank 40 arm, a driving shaft located transversely of the rock shaft, a cam on the driving shaft, a bell crank rocker member having one arm engaging the cam and the other arm engaging the crank arm, a sliding support on 45 which the bell crank member is pivoted, and a screw engaged with the support for shifting the same.

11. In gage mechanism of the character set forth, the combination with movable 50 work-conveying means, of a gage movable into and out of coaction therewith and extending transversely of the conveying means, and mountings for the gage that permit its adjustment with respect to the work- 55 conveying means.

12. In gage mechanism of the character set forth, the combination with movable

work-conveying means, of a gage movable into and out of coaction therewith and extending transversely of the conveying 60 means, and mountings for the gage that permit its adjustment longitudinally of the direction of movement of the work-conveying means.

13. In gage mechanism of the character 65 set forth, the combination with movable work-conveying means, of a gage movable into and out of coaction therewith and extending transversely of the conveying means, and mountings for the gage that permit the adjustment of one end of the gage 70 with respect to the other and with relation to the work-conveying means.

14. In gage mechanism of the character 75 set forth, the combination with movable work-conveying means, of a gage movable into and out of coaction therewith and extending transversely of the conveying means, and a standard on which the gage is mounted, said standard being slidable longitudinally of the work-conveying means. 80

15. In gage mechanism of the character set forth, the combination with work-conveying means, of a gage movable into and out of coaction therewith and including a 85 rock shaft, a sliding standard for the rock shaft having a ball and socket connection therewith, and means for securing the standard against sliding movement and in different positions. 90

16. In gage mechanism of the character set forth, the combination with work-conveying means, of a gage movable into and out of coaction therewith and including a rock shaft extending across the conveying 95 means, standards slidably mounted on opposite sides of the conveying means, ball and socket mountings for the rock shaft on the standards, and means for rocking the shaft. 100

17. In gage mechanism of the character set forth, the combination with a work conveying belt, of a rock shaft thereover, collars on the rock shaft having projecting portions having upright bores, the axes of which intersect the belt, and stop pins adjustably mounted in the bores and having their lower ends coöperating with the belt. 105

In testimony whereof, I affix my signature in the presence of two witnesses.

ALBERT BROADMEYER.
